CLAIM

The ornamental design for a cabinet for dual particle and cell analysis, or similar article, as shown.

DESCRIPTION

FIG. 1 is a perspective view of a cabinet for dual particle and cell analysis or similar article showing my new design;

FIG. 2 is a right side elevational view thereof;

FIG. 3 is a top plan view thereof;

FIG. 4 is a left side elevational view thereof; and

FIG. 5 is a rear elevational view thereof.

FIG. 1

FIG. 2

FIG. 3

FIG. 4

FIG. 5
